United States Patent Office

Des. 223,083
Patented Mar. 7, 1972

223,083

BOTTLE

James E. Plummer, Toledo, Ohio, assignor to Owens-Illinois, Inc., Toledo, Ohio

Filed Oct. 15, 1970, Ser. No. 55,501

Term of patent 14 years

Int. Cl. D9—01

U.S. Cl. D9—113

FIG. 1

FIG. 1 is a front elevational view of a bottle showing my new design;

FIG. 2 is a side elevational view; and

FIG. 3 is a top plan view thereof.

The sides not shown are the same in appearance as the sides shown.

I claim:

The ornamental design for a bottle, substantially as shown and described.
